CLAIM

The ornamental design for a wicker container, as shown and described.

DESCRIPTION

FIG. 1 is a perspective view of a wicker container showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and

FIG. 8 is a perspective view thereof, the container being open.

The continuous weave pattern is shown only partially in FIGS. 2-8 for convenience of illustration.
